14 Claims. (Cl. 250—17)

1

It is known that by modifying the impedance of the coupling slit of a cavity resonator to the outer medium, in any rhythm, the resonator is detuned in the same rhythm and the energy stored in the said resonator is also modified. If a fraction of the said energy be tapped, it is possible thus to produce a centimetre wave which is modulated at the detuned rhythm, and can then be received and detected in a receiver.

The present invention relates to a method of utilising the above mentioned principle for the direct modulation of an ultra-short wave transmitter, and, more particularly, for transmission of the sound, in sound cinematography, between the projection cabin and the screen.

According to the said invention, the impedance of the slit of the resonator is modified by passing in front of it, either, a sound-film strip or, more generally, a strip fabricated expressly for the purpose of modifying the "electric width" of the slit. Accordingly, if such a resonator be tuned to a certain wave length λ_0 , and if it be detuned by some means acting on the resonance frequency, the amplitude of the transmitted wave varies. This resulting impedance-frequency characteristic T represents the coefficient of transmission of the structure including the resonator at the wave length λ_0 . To this end, use may be made, for example, of a strip cut out of a metallised dielectric ribbon, the metallisation being preferably effected in such a manner that its width varies with the intensity of the sound: it is also possible to use a strip of dielectric which is "embossed" in such a manner that the thickness of the dielectric varies in proportion to the sound intensity (strips of plastic material are particularly easy to produce by moulding).

If the quality factor of the resonator be sufficiently great, mere modification of the dielectric constant of the strip of film at musical frequency, by means of the impression usually used, is sufficient to modulate the wave at high frequency. For this purpose, for example, the sound track 2 (Figure 1) of the film 1 is passed in front of the slit 3 of the resonator, the operative length of said slit being naturally limited to the width of the sound track. On the other hand, this coupling slit should be fine enough for the time taken by any point of the film to pass across the slit to be of the order of the smallest musical period used; for a frequency of 10,000 C. P. S., for example, it is found that the width of the slit should be of the order of 0.1 mm. and if such a slit be arranged at right angles to the electric field, resonator quality factors of the order of the critical quality factor are obtained for a wave length of 10 cm.

Figure 2 shows a device according to the in-

2

vention which enables the film 1 to be slid in front of the slit 3 of the resonator 4, which latter may be of any desired shape. The film passes between two parallel flat parts 5 and 6, the latter terminating in two parts 7 and 8 which are bent in the shape of a U having a depth equal to one quarter of the wavelength λ used; this has the effect of preventing the incoming wave from leaking through the passages which are necessarily left open to allow the film to slide and increase the quality factor of the resonator.

Following is a description of a few simple methods according to the invention, which are given by way of non-limitative examples and which enable the principle mentioned hereinbefore to be efficiently carried into practice.

In a first variant of the invention, which is shown diagrammatically in Figure 3, the resonator 4 is constituted by a guide element 9; it is made as short as possible and at its two ends are two conducting planes in which are formed two equal narrow slits 3 and 3'. The film 1 unwinds in front of one of these slits 3' after the fashion of the arrangement of Figure 2. Then, by approaching the critical quality factor, the resonator enables one quarter of the power of the oscillator to be transmitted with a low rate of modulation; said oscillator may, for example, be a magnetron 10 located at one of the ends of the guide 9, between a piston 11 and a slit 12, the guide 9 terminating at the other end in a small transmitting horn 13.

In a second variant of the invention, which is shown diagrammatically in Figure 4, use is again made of a resonator 4 terminating in two slits 14, 15 and placed in a guide 9 provided with a magnetron oscillator 10 at one end and a horn 13 at the other end. The coupling slit 3 with the film 1 is then placed in series with one of the sides 40 of the guide at a distance equal to one quarter of the wavelength λ from each of the slits 14 and 15. In these conditions, a slight variation of the impedance of the slit produces a quick variation of the resonance frequency.

In a third variant of the invention, which is shown diagrammatically in Figure 5, the guide forming a resonator 4 is closed at one end and the coupling slit 3 has the same arrangement as in the first variant. A high frequency tapping 50 16 in this case enables a portion of the modulated wave to be fed to a transmitting aerial 15.

Finally, in a fourth variant of the invention, the film can be made to pass in front of a narrow slit which is dimensioned and shaped in accordance with the device described in the U. S. patent application Serial Number 684,818, entitled "Guides for Radio-Electric Waves Associated with Elements for Regulating the Propagation of

Said Waves." Here the film is passed in front of the portion of the slit forming a capacity; this portion of the slit should, of course, be as narrow as possible.

Although the object of the present invention is not exclusively confined to the use of a modulated centimetric wave transmitter for the transmission of sound in cinematography, it is possible in this particular application to use, for example, the devices shown in Figure 6.

After it has passed through the projection apparatus P, the film 1 passes through the sound detector, the elements of which are those of Figure 3. The receiver (on the right in Figure 6) comprises a diode or a crystal 18 which is fed by a small aerial 19 and is directly followed by a low-frequency amplifier 20 which supplies a loud-speaker 21. The said receiver is located behind the projection screen 17, or beside said screen if the same is metallic. The sound strip could, moreover, be one of the types referred to at the beginning of the specification, and its unwinding could be synchronised with that of the film carrying the pictures. Such a sound cinematography device has, inter alia, the advantages of obviating the use of cables between the projection cabin and the screen and of providing a sound detector which is free from the drawbacks of the usual photo-electric cell.

We claim:

1. A device for the direct modulation of an ultra-short electromagnetic wave, comprising a resonator through which the wave passes and which is coupled to the outer medium, said resonator having a narrow slit provided in one of its walls a modulating strip element with means for passing it in front of said slit, said strip element and said slit being so arranged and formed that the coefficient of transmission for the said wave varies in proportion to the desired modulation.

2. Device according to claim 1, in which said strip comprises the sound track of a sound film.

3. Device according to claim 1, in which said strip is a suitably cut out metal band.

4. Device according to claim 1, in which said strip is a strip of dielectric covered with a metallic deposit the dimension of which in the direction of the length of the slit varies in proportion to the sound intensity to be reproduced.

5. Device according to claim 1, in which said strip is a strip of embossed dielectric, the thickness of the dielectric varying in proportion to the intensity of sound to be reproduced.

6. Transmitter of ultra-short electromagnetic waves which are directly modulated by the use of the device according to claim 1, comprising the combination of a dielectric guide, an ultra-short wave generator located within said guide towards one of its ends, a resonator formed by a portion of said guide limited by two conducting plates, narrow slits in the walls of said resonator including equal narrow slits in said plates for the wave to pass through, said strip element being so arranged as to pass opposite a slit provided in one of the walls of the resonator, and a transmitting means connected to the portion of the guide immediately after the resonator.

7. Transmitter according to claim 6, in which the slit in front of which the strip passes is located in the wall of the guide at a distance from the planes of said conducting plates equal to one quarter of the wavelength, the wave which has passed through the strip being made to pass through an auxiliary guide portion which is closed at its end.

5 8. Transmitter according to claim 6, in which the means for associating the strip with the slit in question comprise a U-shaped part, the bottom of the U being located opposite and at a short distance from the slit and being itself provided with a slit located in alignment with the first-mentioned slot, the arms of the U being of a length equal to one quarter of the wavelength used, so as to prevent the wave from leaking out 10 of the guide through the spaces provided to allow the strip to move.

9. Transmitter according to claim 6, in which the slit in front of which the strip passes is one of the two slits provided in said conducting plates 15 of the resonator.

10. Transmitter according to claim 9 in which the slit is shaped like a U, the arms of which, acting as an inductive impedance in shunt, are parallel, and the bottom of which is at right angles to the lines of the electric field, the strip moving parallel to said arms, so that only the impedance of said bottom acting as a capacity in parallel is modified at the modulating frequency.

25 11. Method of transmitting at a distance a recording in the form of a band by direct modulation of the amplitude of an ultra short wave traversing a wave guide having in its interior and along the course of said wave a cavity resonator tuned to the frequency of said wave, comprising moving said band relatively to said cavity resonator so as to modify the impedance condition of the cavity resonator, and causing thereby 30 a direct modulation of the amplitude of said wave in accordance with the recording on said band.

12. Method according to claim 11, in which said cavity resonator has a plurality of slits in its walls two of which are in the traverse path of said wave, and including the step of moving said band past one of said slits.

13. Method according to claim 12, including moving said band past a lateral slit not in alignment with said two slits.

40 14. Device for transmitting at a distance a recording in the form of a band, comprising a wave guide, means coupled to said guide for feeding in an ultra short wave of predetermined frequency, a cavity resonator located within said guide in the traverse path of said wave and tuned to the frequency of said wave, said resonator comprising two conductive diaphragms arranged perpendicularly to the longitudinal axis of the guide each provided with a fixed slit, the said slits being parallel, and means coupled to said resonator for causing said band to pass in front of one of said slits.
